CLAIM

The ornamental design for a coffee cup, as shown and described.

DESCRIPTION

FIG. 1 is a perspective view taken from slightly to the left and slightly above the cup of the present invention.

FIG. 2 is a view corresponding to FIG. 1, but taken from slightly to the right of the cup.

FIG. 3 is a front view of the cup (the back view is identical)

FIG. 4 is a right hand view of the cup (the left hand view is identical)

FIG. 5 is the top view of the cup; and,

FIG. 6 is the bottom view of the cup of the present invention.
